(57) **CLAIM**

The ornamental design for a trail camera mounting device, as shown and described.

DESCRIPTION

FIG. 1 is a side elevational view of a trail camera mounting device in an operative position securing the trail camera mounting device to a tree, showing my new design.

FIG. 2 is an exploded, perspective view of the trail camera mounting device of FIG. 1.

FIG. 3 is an assembled, perspective view of the trail camera mounting device thereof.

FIG. 4 is an enlarged, front elevational view of the trail camera mounting device of FIG. 3 rotated ninety degrees.

FIG. 5 is a left side elevational view of FIG. 3.

FIG. 6 is a right side elevational view of FIG. 3; and,

FIG. 7 is a rear elevational view of FIG. 3.

The broken lines shown in FIG. 1 represent the environment of the claimed design and form no part of the claimed design.
